UNITED STATES PATENT OFFICE

JAMES J. REGAN, OF LOS ANGELES, CALIFORNIA

STEAM BOILER

Application filed March 12, 1929. Serial No. 346,354.

This invention relates to a steam boiler construction embodying the super-heating principle.

Among the objects of the invention is to provide a boiler tube construction which can be readily assembled, easily disassembled for cleaning, which will not be apt to leak, and which will be more durable, economical, and dependable in its operation than boilers which relate most nearly to its type.

Other objects and advantages may herein-after appear.

Referring to the accompanying drawings which illustrate at present deemed to be a preferred embodiment of the invention,

Fig. 1 is a vertical sectional view of a complete boiler construction built according to the principles of the invention.

Fig. 2 is a view partly in elevation and partly in section of the construction shown in Fig. 1, the sectioned portion being indicated by line 2-2 on Fig. 1.

Fig. 3 is a transverse section of the super-heating coil and adjacent parts on line 3-3 of Fig. 1.

Fig. 4 is a cross section on line 4-4 of Fig. 3.

Fig. 5 is a cross sectional detail on line 5-5 of Fig. 1.

Referring in detail to the drawings, within the main chamber 5 are mounted in superposed series the outer tubes 6 which, as viewed in Fig. 1, are supported at their left ends by the inner header plate 7 into which they are screwed, said tubes 6 being supported near their right ends by the header plate 8 and having their right ends closed with caps 9.

Within said outer tubes 6 are telescoped the inner tubes 10, the left ends of said tubes 10 being screwed into the intermediate header plate 11.

There are a multiple of the parallel upright headers 12, as shown in Fig. 2 each having a water and steam piping system comprising pipes 6, 10, 25b, 26, 30 and 31, as will herein-after be described.

Cold water is supplied through a pipe 15 to the chamber 16 within water jacket 8, through connection 22 into the lower portion of water jacket 23. With jacket 23 com-

municates pipe 33 which leads past valve 24 to nipple 35 which connects with the pump 34. Pump 34 has an outlet pipe 37 which leads to chamber 55 of header 54. The inner chamber 56 of said header 54 is provided with an outlet pipe 57, which is a branch of pipe 40. Said pipe 40 is at each end connected to drum 25 by means of a branch pipe 40a.

An emergency pipe 36, controlled by a valve 36a is connected to nipple 35 as shown.

In the upper portion of the chamber 5 is located a heat economizing system 19 of outer tubes 20 and inner tubes 21 which are in communication with chamber 55c of header 54 and which are assembled in relation to each other according to the plan already described with reference to the tubes 6 and 10. Said outer tubes 20 communicate with the inner header chamber 56.

The steam and water drum 25 is supplied with steam through a steam pipe 26 which leads to the interior of said drum in the chamber 27 of which the steam collects. Pipe 25b leads from the lower side of drum 25 to each header chamber 28.

At the lower end of the chamber or spaces 28 and 29 are provided respectively the clean out pipes 30 and 31 which communicate with the portion of said chambers where the sediment settles.

Describing the construction more in detail, and beginning at the point where the cold water feed pipe 15 is located, from said pipe 15 water is fed to the lower end of the cooling jacket 8. As well shown in Fig. 1 said cooling jacket is spaced somewhat to the left of the closure caps 9 with which the outer tubes 6 are closed at their ends, and the upper end of said jacket is provided with an outlet branch pipe 33 which leads to the pump 34 through the nipple 35. If for any reason it becomes necessary to supply cold water directly to the pump 34 this may be conducted through the emergency pipe 36, having valve 36a, which also is connected up with said nipple 35.

Said pump 34 is provided with an outlet pipe 37 which leads to the auxiliary series 19 of heating tubes 20 and 21, said tubes 20 each

55

80

85

90

95

100

having a tube 21 arranged within it, the construction and arrangement of these tubes with relation to each other being the same as that of the tubes 6 and 10 already described.

5 From the auxiliary series of tubes the water is led through pipe 40 to the steam and water drum 25.

10 Each of the outer tubes 6 is, as seen in Fig. 1, provided at its left end with right hand external screw threads which screw into the intermediate header plate 7. The caps 9 which close the right ends of said tubes 6 are provided with threads which are reversely cut to the threads in the header 7.

15 The housing 31 is divided longitudinally by partition 31w into two chambers 31c and 31d. Each of pipes 30 communicates with chamber 31c, and each of pipes 31 communicates with chamber 31d, thus forming an efficient clean-out system for the entire system. Chamber 31c is provided at each end with a draw off pipe 31e, and chamber 31d is provided at each end with a draw-off pipe 31f.

20 Chambers 55 and 56 (see Fig. 4), are respectively provided with clean out pipes 57 and 58, both of which communicate with pipe 59 through intermediate connection 60, to provide for cleaning the heat-economizing system.

25 30 Into the main series of tubes extends a baffle plate 47, parallel with said tubes and occupying the right hand portion of the apparatus as viewed in Fig. 1. In the upper right hand portion of the fire-box 52 as seen in this view, is shown a baffle wall 48. The baffle wall 48 is preferably shorter than the baffle wall 47 in order that the first whirling effect given to the heated gases may be reversed by the upper baffle 47 as the air passes up between the boiler tubes.

35 40 Upon passing baffle 47 the column of heated gases is deflected against the headers 12, whence, by the suction of stack 50 it is reversely drawn through upper tubes of the main coil system and thereafter through auxiliary or heat-economizing system 19.

45 Referring to external elements of the apparatus, the upper outer casing 45 is provided with a front door 50 to conserve the heat and to afford access to the sections of the header 12. The apparatus is provided with a stack 50 having therein a damper 50d. A back door 55 is preferably provided. All parts are provided with suitable layers of insulating material as shown.

50 A check valve 57a in pipe 57 prevents back flow of drain water.

55 Both end portions of the series of superposed pipes 6 are enclosed by water jackets which keep down the temperatures of the corresponding end walls of the combustion chamber. A like construction of jackets cools both ends of the series of auxiliary superposed pipes 19. The water or water and

steam circulates through all these jackets in its advance.

60 The auxiliary series of pipes 19 extends at substantially right angles to the main series of pipes 6, hence the flame in passing up through all these pipes of both series is subdivided in a more efficient manner and a more complete absorption of the heat is effected than if all the heating pipes of the system extended in the same direction. 70

75 In operation, the feed water pipe 15 being connected to a water pipe under city pressure, or to any other suitable supply, water from said pipe 15 is fed to the lower end of the cooling jacket 8 and after passing up through said jacket is drawn through connection 22 into the lower portion of water jacket 23. In passing through this water jacket the cold water coming from the pressure supply not only keeps down the temperature of the end wall of the combustion chamber but also gives a preliminary heating to the liquid as it passes from said pressure supply toward the pump 34 which it reaches later in its course, and whereby the pressure is stepped up sufficiently to cause the liquid and steam to advance as required. After passing through said jacket it issues from the upper end thereof through pipe 33, thence by way of nipple 35 to the pump 34. 80

85 To control the flow as just described valve 24 is open and valve 36a is closed. From pump 34 it is forced up through the pump outlet pipe 37 through chamber 55 of header 54, thence through the auxiliary coil 19, passing first into the inner tubes 21 of said coil and thence into the outer tubes 20 thereof, after which it is conducted into chamber 56 then out through pipe 57a thence out through pipe 40 and its branches 40a into the drum 25. The hot water thus supplied to said drum, after being further heated therein, flows out through the drum outlet pipe 25b whereby it is conducted to the upper end of the outer header chamber 28. From the outer header chamber 28 the water passes through the series of inner tubes 10 through the header plate 11 whence, as seen in Fig. 1, it is discharged into the right hand end portions of the outer tubes whereby it is reversely directed to the inner header chamber 29 whence it escapes as steam from the upper end of said chamber through the steam pipe 26 to the steam drum 25. 95

100 Claim:

105 In a boiler construction, a steam and water drum, a main boiler tube section comprising a main series of superposed parallel pairs of water heating tubes, each of said pairs consisting of an outer tube and an inner tube telescoped within said outer tube, all of said tubes having open ends which are located at the same side of the boiler tube section, means to wall off the portion of said chamber which is occupied with the open ends of said tubes 110

115

120

125

130

to provide two chambers, one of which is in communication with the outer series of tubes and the other of which is in communication with the inner series of tubes, conduits where-
5 by each of said two chambers are separately connected with said steam and water drum, a cooling jacket through which said tele-
scopically arranged tubes project adjacent to the other side of said main boiler tube
10 section, an axially boiler tube section located above said main boiler tube section and con-
sisting of inner and outer tubes having also two chambers into which their open ends dis-
charge and a cooling jacket adjacent to their
15 other ends, there being conduits arranged to conduct the fluid first through the cooling jacket of the main series of tubes and next through the cooling jacket of the auxiliary series of tubes, and conduits leading the fluid
20 thence through the inner and outer tubes of the auxiliary series of tubes and through the last recited two chambers, and means to conduct the water thus heated to the aforemen-
tioned steam and water drum.

25 In testimony whereof I hereunto affix my signature.

JAMES J. REGAN.
